CLAIM

The ornamental design for a charging dock for electric toothbrush, as shown and described.

DESCRIPTION

FIG. 1 is a front perspective view of a charging dock for electric toothbrush of the present disclosure;

FIG. 2 is a rear perspective view of the charging dock for electric toothbrush shown in FIG. 1;

FIG. 3 is a front elevational view of the charging dock for electric toothbrush shown in FIG. 1;

FIG. 4 is a rear elevational view of the charging dock for electric toothbrush shown in FIG. 1;

FIG. 5 is a left-side elevational view of the charging dock for electric toothbrush shown in FIG. 1;

FIG. 6 is a right-side elevational view of the charging dock for electric toothbrush shown in FIG. 1;

FIG. 7 is a top plan view of the charging dock for electric toothbrush shown in FIG. 1; and,

FIG. 8 is a bottom plan view of the charging dock for electric toothbrush shown in FIG. 1.

The broken lines shown in the drawings are for the purpose of illustrating portions of the charging dock for electric toothbrush that form no part of the claimed design.

1 Claim, 8 Drawing Sheets
